US00D758834S

(12) **United States Design Patent**
Tally

(10) **Patent No.:** **US D758,834 S**
(45) **Date of Patent:** **** Jun. 14, 2016**

(54) **ROOFTOP SUPPORT**(71) Applicant: **Cooper Technologies Company**,
Houston, TX (US)(72) Inventor: **Brandon Michael Tally**, Greenville, IL
(US)(73) Assignee: **Cooper Technologies Company**,
Houston, TX (US)(***) Term: **15 Years**(21) Appl. No.: **29/535,607**(22) Filed: **Aug. 7, 2015****Related U.S. Application Data**

(62) Division of application No. 29/465,729, filed on Aug. 30, 2013, now Pat. No. Des. 738,711.

Primary Examiner — Rosemary K Tarcza*Assistant Examiner* — Nathaniel D Buckner(74) *Attorney, Agent, or Firm* — Sennier Powers LLP(57) **CLAIM**

The ornamental design for a rooftop support, as shown and described.

DESCRIPTION

FIG. 1 is a perspective of a rooftop support;

FIG. 2 is a front elevational view thereof;

FIG. 3 is a right elevational view thereof;

FIG. 4 is a top plan view thereof;

FIG. 5 is a rear elevational view thereof;

FIG. 6 is a left elevational view thereof; and,

FIG. 7 is a bottom plan view thereof.

The broken lines in the drawings indicate environmental structure which forms no part of the claimed design.
